DESIGN FOR A PRINTER'S SAW

Glenn W. Tammen, Chicago, Ill., assignor to American Type Founders, Inc., Elizabeth,
N. J., a corporation of New Jersey

Application December 28, 1939, Serial No. 39,174

Term of patent 7 years

To whom it may concern:

Be it known that I, Glenn W. Tammen, a citizen of the United States, residing at Chicago, county of Cook, and State of Illinois, have invented a new, original, and ornamental Design for a Printer's Saw, of which the following is a specification, reference being had to the accompanying drawing figures, forming part thereof.

I claim as my invention:

The ornamental design for a printer's saw, as shown.

GLENN W. TAMMEN.
